T. RALFS

SAW VISE

Filed May 19, 1921

INVENTOR
Theodore Ralfs,
BY Walter N. Haskell
his ATTORNEY

UNITED STATES PATENT OFFICE.

THEODORE RALFS, OF DAVENPORT, IOWA.

SAW VISE.

Application filed May 19, 1921. Serial No. 470,772.

To all whom it may concern:

Be it known that I, THEODORE RALFS, a citizen of the United States, residing at Davenport, in the county of Scott and State 5 of Iowa, have invented certain new and useful Improvements in Saw Vises, of which the following is a specification.

My invention has reference to improvements in saw vises, such as are used for the 10 purpose of holding the blade of a saw in position while the same is being filed or otherwise operated on. The chief purpose thereof is to provide means for clamping or gripping the blade which will be quick acting, so that the blade can be instantly released for adjustment or removal, or quickly placed in position. It is also arranged so 15 that the jaws can be placed and held in adjusted positions, with relation to the bench 20 on which the tool is supported.

In the drawings:

Fig. 1 shows my invention in front elevation.

Fig. 2 is a side elevation thereof.

Fig. 3 is a detail of the shaft 14.

1 is a vertical arm, fitted at its lower end with spaced-apart plates 2, having a pivotal connection with a bracket 3, projected from a clamp 4, provided with a screw 5, whereby 25 the clamp can be attached to a table or bench. The parts 2 and 3 are pivoted by means of a bolt 6, provided on one end with a thumb-nut 7, by means of which the plates 2 can be caused to embrace the bracket 3, and 30 hold said plates from movement. At its upper end the arm 1 is provided with a clamp-plate or jaw 8.

The lower part of the arm 1 is projected 40 forwardly and upwardly into a pair of arms 9, spaced apart from the arm 1 a desired distance, and between the upper ends of the arms 9 is pivoted a lever 10, provided at its upper end with a clamp-plate or jaw 11, in opposition to the jaw 8, and adapted to be 45 brought into contact therewith. The lower

part of the arms 9 is formed with a bearing 12, having bearings 13, in which is supported a shaft 14, passing through an opening in the lower part of the arm 10, and provided at one end with a handle 15. At the point 50 where said shaft passes through the arm 10 it is provided with an off-set portion 16, so disposed that when the handle 15 is turned upwardly, as shown in the figures, the lower end of the arm 10 is held in an outward position. This holds the jaw 11 in operative position with relation to the jaw 8, so that a saw-blade which is placed between such jaws is held rigidly in position therein. When it is desired to release the saw, the 55 handle 15 is turned downwardly, moving the lower arm of the lever 10 inwardly.

By releasing the thumb-nut 7 the vise can be tipped toward the bench or away therefrom, so as to support the saw blade in an inclined position with relation thereto. For some operations this would place such 60 blade in a more convenient position.

What I claim and desire to secure by letters patent, is:

A device of the class described, comprising 70 a screw clamp adapted to be secured on a work bench or like object, a clamping bolt in a portion of the clamp, an upwardly directed member pivoted with its lower end on said clamping bolt and forming a rear arm with a vise jaw at its upper end and two front arms parallel to the rear arm, a beam lever fulcrumed between the front arms and having at its upper end a vise jaw arranged 75 to coact with the first mentioned jaw and its lower end depending between the front arms, a horizontally disposed crankshaft journaled in the two front arms and engaged with the lever to swing it, and a hand lever 80 fixed at one end of the crankshaft for imparting rotary movement to the same.

In testimony whereof I affix my signature.

THEODORE RALFS.
